UNITED STATES PATENT OFFICE

2,480,993

VENETIAN BLIND

Charles Adler, Cincinnati, Ohio

Application August 8, 1946, Serial No. 689,153

3 Claims. (Cl. 160—173)

1

This invention relates to improvements in Venetian blinds and particularly to the so-called "hardware" for mounting the raising and lowering rope or ropes.

In the past when it was desired to replace or change the rope or ropes associated with a Venetian blind for raising and lowering the slats thereof, it was necessary to completely remove the blind from the window or other opening and completely disassemble it whereupon the blind had to be reassembled practically slat by slat. This same condition existed with respect to the replacement or changing of the so-called "ladder" tape which holds the slats in their spaced apart relation when the blind is in extended position.

By this invention each of the foregoing disadvantages of a Venetian blind is eliminated.

It is, therefore, the principal object of the present invention to provide a Venetian blind wherein the raising and lowering cord can be readily and easily replaced.

Another object of this invention is the provision of a Venetian blind, and particularly the hardware thereof, whereby the blind including the head rail, tilt board, slats and bottom rail can be assembled in a minimum of time and with a great saving in time over the assembly of said parts as required in the past.

Another object of this invention is the provision of a Venetian blind wherein the slats raising and lowering cord can be changed while the blind is hanging in its normal position.

A further object of this invention is the provision of a Venetian blind wherein the raising and lowering cord and the slat spacing tapes can be changed or replaced without removing the blind from its opening, disassembling the blind in any manner, and wherein the said ladder tape or slat spacing tape can be replaced without removing the raising and lowering cord.

A still further object of this invention is the provision of hardware for use in a Venetian blind to accomplish the foregoing objects and which hardware is simple in construction and economical to manufacture.

A still further object of this invention is the provision of a simple wire clip which cooperates with the ladder steps of the ladder tapes to prevent the lateral or other shifting of the said tapes during the operation of the blind.

Other objects and advantages of the present invention should be readily apparent by reference to the following specification considered in conjunction with the accompanying drawings forming a part thereof and it is to be understood that

2

any modifications may be made in the exact structural details there shown and described, within the scope of the appended claims, without departing from or exceeding the spirit of the invention.

5 In the drawings:

Fig. 1 is an elevational view of a Venetian blind illustrated as mounted in a window-opening and which blind incorporates the improvements of this invention.

10 Fig. 2 is a vertical sectional view through the blind of Fig. 1 taken on line 2—2 on said Fig. 1.

Fig. 3 is an enlarged fragmentary view partly in section and partly in elevation taken on line 3—3 of Fig. 1.

15 Fig. 4 is a fragmentary vertical sectional view taken on line 4—4 on Fig. 3.

Fig. 5 is a perspective view of a plate or bracket utilized in mounting the ladder tapes and forming a detail of the invention.

20 Fig. 6 is a fragmentary perspective view of a ladder tape utilized in carrying forward the present invention.

Fig. 7 is an enlarged bottom plan view of a portion of a slat of a Venetian blind showing the improved clip of the present invention and seen from line 7—7 on Fig. 6.

25 Fig. 8 is a fragmentary elevational view of the head rail of a Venetian blind having mounted thereon the hardware of the present invention.

30 Fig. 9 is a view partly in section and partly in elevation illustrating the cord lock as seen from line 9—9 on Fig. 8.

Fig. 10 is a vertical sectional view of the cord lock taken on line 10—10 on Fig. 9.

35 Fig. 11 is a perspective view of the locking dog associated with the cord lock of the present invention and forming a detail of the invention.

Fig. 12 is a fragmentary view partly in section and partly in elevation showing the mounting of 40 the tilt bar of a Venetian blind as seen from line 12—12 on Fig. 8.

Fig. 13 is a transverse sectional view through one of the cord roller supports as seen from line 13—13 on Fig. 8.

45 Fig. 14 is a perspective view of a cord roller and its mounting bracket.

Fig. 15 is a view similar to Fig. 8 illustrating a head rail and a modification of the mechanism 50 for accomplishing the purposes of the present invention.

Fig. 16 is a vertical sectional view through the cord lock of Fig. 15 taken on line 16—16 on said Fig. 15.

55 Fig. 17 is a sectional view through the cord roller

of the modification in Fig. 15 taken on line 17—17 on said Fig. 15.

Fig. 18 is a transverse sectional view through a further modification in the details of the invention and a construction which may be substituted for that illustrated in Figs. 13 and 17.

Fig. 19 is a fragmentary perspective sectional view of a ladder tape showing a construction thereof of somewhat different from that of Fig. 6 but accomplishing the same purposes as the construction of said Fig. 6.

Fig. 20 is an enlarged vertical sectional view through a portion of the Venetian blind as seen from line 20—20 on Fig. 1.

Throughout the several views of the drawings similar reference characters are employed to denote the same or similar parts.

This application discloses additional improvements in Venetian blinds and their construction over that disclosed in applicant's pending applications Serial Numbers 609,069 and 667,870 now U. S. Patent 2,471,710 issued May 31, 1949.

The Venetian blind as heretofore known and used comprises a head rail 20 mounted relative to an opening illustrated in the drawings by a window frame 21 with the head rail secured thereto by brackets 22 and 23. Below the head rail 20 is a tilt bar 24 pivotally carried by the head rail through any suitable or desirable means such as the bracket 25 at the left hand of the tilt bar and the depending member 26 at the right hand thereof. The depending member 26 forms a part, as is usual construction, of the cord locking mechanism and will later be described in detail. The tilt bar bracket 25 is a part of the tilting mechanism indicated in the drawings by the reference numeral 27 from which depends cords 28 and 29 whereby the said mechanism 27 is actuated for oscillating the tilt bar 24 about its longitudinal axis.

Below the tilt bar 24 are the slats 30 which vary in number depending upon the height of the opening to be covered and the slats further varying in number depending upon the width of the individual slats. The slats are spaced from one another by tape assemblies 31 and 32 which have their upper ends secured to the tilt bar 24 by means to be subsequently described and which tape assemblies have their lower ends secured to a bottom rail 33.

Each of the tape assemblies 31 and 32 is substantially identical and as particularly illustrated in Fig. 6 comprises a forward flexible tape member 34 and a rear flexible tape member 35. The tape members 34 and 35 each have a similar opposed vertical edge spacedly connected to the other by a plurality of slat supporting members or ladder steps 36, there being as many slat supports or ladder steps 36 as there are slats in the blind. The ladder steps or slat supports 36 are illustrated in the drawings as having their opposite ends 37 and 38 secured, respectively, to the inner opposed surfaces of the tape lengths 34 and 35. It should be noted however that in the manufacture of a tape assembly the said ends 37 and 38 are in reality woven into the tape lengths 34 and 35 thereby resulting in merely a thickening of said tape lengths at the points of securing of the said ladder supports.

It will be noted from Fig. 6 that the slat supports or ladder steps 36 are mounted one below the other in a vertical alignment and each on the same side of the raising and lowering cord 39 which passes between the tape lengths 34 and 35. This is the ideal construction while with certain

of the weaving looms now in use the said slat supports or ladder steps can not be so formed but must be offset from one another whereby alternate ladder steps are in vertical alignment but are offset with respect to the adjacent step above and below. This construction is illustrated in Fig. 19 wherein the tape length is indicated by the reference numeral 35', the slat supports or ladder steps by the reference numeral 36' and the ends of said slat supports or ladder steps by the reference numeral 38'.

Any suitable or desirable means may be employed for securing the tape lengths 34 and 35 of the tape assemblies to the tilt bar 24 that illustrated in the drawings being a preferred one for purposes of illustration only. The means there described comprises a bracket 40 illustrated as a flat member relatively thin and substantially U shaped in plan including a base 41 and arms 42 and 43 extending from the ends of said base. The arms 42 and 43 are each, respectively, provided with an elongated rectangular opening 44 and 45 into which the ends of the tape layers 34 and 35 are respectively inserted. The ends of said tape layers 34 and 35 are respectively secured to the bracket 40 by each having secured thereto a metal clip or end 46 which has a length slightly greater than the length of its aperture wherefore it impinges against the under side of its plate beyond said aperture and cannot be pulled through the aperture by a direct pull on the tape. In order to secure the bracket 40 in position on the tilt bar it is provided with apertures 47 through which extend screws 48.

The attachment of the lower ends of the tape lengths 34 and 35 to the bottom rail 33 may be accomplished in any suitable or desirable manner, that illustrated in the drawings consisting merely of folding the lower ends 49 and 50 of said tape lengths 34 and 35 onto one another against the under surface of the bottom rail 33 and passing therethrough suitable fastening members such as tacks 51. This method of fastening the lower ends of said tape members is clearly illustrated in Fig. 20.

In the past it has been customary to form the slat supports or ladder steps 36 alternately on opposite sides of the vertical center thereof whereby the said slat supports or ladder steps alternately engaged opposite sides of the raising and lowering cord 39. By the present invention, and that of the aforementioned co-pending application Serial No. 667,870, all of the ladder steps or slat supports are on the same side of the cord 39 and will prevent the shifting of said tape assembly transversely of the blind that requires crossing the said cord. To insure the tape assembly from shifting in the opposite direction use may be made of the clip illustrated in Fig. 7 and indicated in general by the reference numeral 52.

The clip 52 consists of a single length of wire bent on itself to provide a loop having legs 53 and 54 which slightly diverge from their joined end 55. The legs 53 and 54 then converge and cross one another as arms 56 and 57 with each arm having, respectively, at its outer end a reverse curve 58 and 59 terminating in spring fingers 60 and 61. The fingers 60 and 61 may be slightly offset from their arms 56 and 57 whereby they engage and straddle the slat 30. This attachment of the clip 52 is accomplished by having its legs and arms lying against the under side of the slat with their spring fingers passing upwardly through the elongated aperture 62 in said

slat to lie on the upper surface thereof at the opposite ends of the said aperture 62. In practice the slat support or ladder step 36 passes through the loop with, as seen in Fig. 7, the loop leg 53 on one side thereof and the loop leg 54 on the other. The operation of the clip 52 is believed obvious in preventing lateral shifting of the tape assemblies since, as noted above, the raising and lowering cord by engaging the ladder step or slat support 36 prevents this shifting in one direction and the clip base or bend 55 engages the said slat support or ladder step to prevent this shifting in the other direction. It should be noted that the aperture 62 is provided in each slat and in the tilt bar in alignment with one another for the passage therethrough of the raising and lowering cord 39. Actually there are two such apertures 62 in each slat and tilt bar, one near each end, through each of which passes a raising and lowering cord, one of which cords is indicated by the reference numeral 39 while the other is indicated by the reference numeral 63.

The raising and lowering cords 39 and 63 may be separate cords but generally are merely the ends of a continuous cord which extends to the inside surface of the Venetian blind and are joined as at 64 in Fig. 1. In the past the said raising and lowering cord passed through a so-called cord lock which locks the cord against movement for thereby locking the slats in adjusted positions, in reality, locking or fixing the height of the bottom rail 33 above the bottom of the opening with which the Venetian blind is used. The said raising and lowering cords also are utilized for causing all of the slats to be superimposed directly on one another at the upper end of the opening and occupy a position immediately below the tilt bar 24. In the past the said raising and lowering cords passed upwardly through the cord lock into a channel along the upper surface of the head rail 20 and then passed through suitable apertures in said head rail to be threaded through the slat apertures 62. In order to change the said raising and lowering cords and when initially assembling a Venetian blind the parts were removed from the opening and the cords threaded through the lock and the various apertures, an operation quite tedious and time consuming. By the present invention the cords are not threaded through the cord lock nor through apertures in the head rail and the said cord may be replaced without removing the head rail from the opening and can be accomplished by unskilled labor in a minimum of time and with a minimum of effort.

The improved cord lock of the present invention and indicated in general by the reference character 65 is substantially a tubular member rectangular in cross section and comprising a back 66, sides 67 and 68 and a front 69. The back 66 is extended and turned at an angle thereto to provide a mounting flange 70 through which screws 71 pass for securing the cord lock to the under surface of the head rail 20. The upper end of the housing front 69 is spaced below the under surface of the head rail thereby providing an opening 72 between the under surface of the head rail and top of the cord lock. Within the housing and rotatably mounted on a shaft 73 is a double grooved pulley 74 one groove of which receives the raising and lowering cord 39 while the other receives the raising and lowering cord 63. Below the pulley 74 and mounted on a pivot pin 75 is the locking dog 76 which has its free end serrated to provide teeth 77 that cooperate with

the cords 39 and 63 in locking them relative to the housing.

The housing front 69 and right hand side 67 (as seen in Fig. 8) is each provided with a cutout 5 which as seen in Figs. 8 and 9 has a vertically disposed path 78 followed by an upwardly outwardly inclining portion 79. The path of the opening continues in the housing side 67 by an upwardly outwardly inclining portion 80 and a final directly vertically disposed portion 81. In other words this opening 78-81 is continuous through the housing front 69 and housing side 67 through which the raising and lowering cords 39 and 63 may be inserted into the housing. From this it follows that the said raising and lowering cords need not be threaded upwardly through the locking mechanism housing but can be placed therein through the said opening 78-81 and this can be accomplished while the head rail is securely mounted in position in the opening with which the blind is to be employed or the said raising and lowering cords can be arranged with respect to the cord lock while the head rail is lying on its side on a work bench or the like.

As seen in Fig. 8 the locking dog 76 crosses the housing opening to thereby prevent the passing therethrough of the said raising and lowering cords, the locking dog is retained in this position by a removable pin 82 against which it is resting as illustrated in Fig. 8. Removal of the pin 82 will permit the locking dog to fall by gravity to the position illustrated in phantom lines at 83 in Fig. 10 thereby completely uncovering the housing opening and permitting the insertion of the cord as above described. After the cord has been disposed within the housing the said pin 82 is returned to the position illustrated in Figs. 8 and 9 thereby positioning the locking dog 76 to prevent inadvertent displacement of the cord through the housing opening 78-81 and at the same time positioning the locking dog 76 to engage the raising and lowering cords to lock them in operative position. It is believed the operation of the cord locking mechanism for locking the cords is well known however the said cords travel upwardly, as viewed in Figs. 8, 9 and 10, for lowering the Venetian blind and when the bottom rail has reached the desired elevation the said cords are actuated to the left as seen in Fig. 8 thereby causing a frictional engagement of the said cords and the locking dog teeth 77 whereupon the locking dog moves with the raising and lowering cords to be actuated from the position shown in Fig. 8 to the solid line position 84 of Fig. 10 which impinges the cords between itself and the housing side 67. It will be appreciated that force on said ropes in a direction to cause an upward movement thereof will only more tightly jam the locking dog raising and lowering cords and housing side. As is well known if it is desired to subsequently adjust the Venetian blind it is only necessary to exert a downward pull on the cords as seen in Fig. 8 which will release the dog 76 and permit it to fall by gravity to the position illustrated in Fig. 8 whereupon the blind may be either raised or lowered and subsequently locked in its adjusted position for again merely engaging the cord lock teeth 77 with the raising and lowering cords.

In order to prevent loss of the pin 82 it may be attached to the cord lock 65 as by a flexible attaching member 82' which has one end secured to the pin 82 and the other end secured to the cord lock housing.

The said raising and lowering cords after passing through the cord lock 65 extend to a pulley

mechanism indicated in general by the reference numeral 85. This pulley mechanism 85 comprises a U-shaped bracket having a front 86, a back 87 and a bottom 88. The bottom 88 however does not extend completely the length of the front and back 86 and 87 but extend only approximately half way thereby permitting an opening through said bottom to permit the raising and lowering cord to pass therethrough. The bracket back 87 has at its upper end, at an angle thereto, a flange 89 through which passes screws 90 for securing the pulley mechanism to the under side of the head rail 20. The bracket front 86 is of less height than the back 87 and is therefore spaced below the under surface of the head rail 20 thereby providing an opening 91 through which the cords pass to be disposed interiorly of the pulley mechanism. Within the pulley housing is a double grooved pulley 92 rotatably mounted on a pivot pin 93 extending between the said bracket front and back 86 and 87.

The pulley 92 receives in one of its grooves the raising and lowering cord 39 and in its other groove the raising and lowering cord 63 and which latter cord is illustrated as depending from the bracket mechanism 85 to and through the tilt bar, individual slats and bottom rail to which it is secured as will later be made clear.

The raising and lowering cord 39 passes beyond the pulley mechanism 85 to a second pulley mechanism indicated in general by the reference numeral 94. This pulley mechanism 94 is substantially identical with the pulley mechanism 85 and its description above is deemed to suffice. It should be noted however that the pulley mechanism 94 has an opening 95 between the upper end of its bracket front and the under surface of the head rail 20 which is substantially identical with the opening 91 between the upper end of pulley mechanism front 86 and the under surface of the head rail 20.

As was noted above, in the past, the tilt bars 24 were provided with elongated apertures through which the raising and lowering cords passed. By the present invention the said tilt bar 24 is provided with a notch or slot 96 which extends through one side of the tilt bar, there being a separate notch for each of the raising and lowering cords. This construction is particularly advantageous when replacing the improved ladder tapes of this invention and that disclosed in the above identified application Serial No. 667,870.

The lower ends of the raising and lowering cords 39 and 63 may be secured to the bottom rail 33 in any suitable or desirable manner, for example, as shown in the drawings, particularly Fig. 20, the said bottom rail is provided with an aperture 97 through which the cord passes having its free end formed as or tied into a knot 98 to engage a shoulder 99 intermediate the ends of the aperture.

The means for securing the tilt bar to the head rail, as noted above, is at one end by means of the tilting mechanism bracket 25 and at the other end by depending member 26. This depending member 26, as shown in Figs. 8 and 12, comprises an extension 100 of the locking mechanism housing side 68. The said extension having formed therein a bayonet slot 101 receiving the pivot pin 102 from the tilt bar 24. The pivot pin 102 is locked in its slot 101 by a latch member 103 pivoted at 104 to the bracket extension 100.

When it is desired to replace the raising and lowering cords 39 and 63 the Venetian blind is

actuated to its uppermost position whereupon the slots are in superimposed contacting relation to one another. The ends of the ladder tape sections 34 and 35 are then released from their brackets 40 by feeding the metal ends or clips 46 thereof through the slots 44 and 45. The raising and lowering cords are then released from the cord lock whereupon the Venetian blind slats and their ladder tape assemblies 31 and 32 now collapsed are lowered as a unit to the bottom of the opening frame 21 to rest on the sill 105 thereof. The lower ends of the tape members 34 and 35 are released from the bottom rail 33 thereby exposing the cord knots 98. Opening of said knots will permit the raising and lowering cord ends to be drawn through the aligned apertures 62 of the slats. The said slats are retained in their collapsed position which presents a relatively short opening through which the ends of the new cords may be inserted which upon being inserted through the apertures 97 in the bottom rail 33 are knotted and drawn back against the aperture shoulders 99. The ends 49 and 50 of the tape lengths 34 and 35 are then retacked to the bottom rail 33 over the apertures 97 therein. The said raising and lowering cord 39 is then passed through the opening of pulley mechanism 94 and the cords 39 and 63 are then inserted through the opening 91 of pulley mechanism 85 whereupon the said cords are passed through the opening 78-81 of the cord lock mechanism 65. It is understood, of course, that the old raising and lowering cords were removed after their knots 98 were opened and that the movable pin 82 of the cord lock mechanism had been removed to permit the locking dog 76 to take the position illustrated at 83 in Fig. 10. After the new raising and lowering cord has been positioned within the cord lock 65 the locking dog 76 is actuated to the position illustrated in Fig. 8 and the pin 82 replaced.

The Venetian blind slats along with the bottom rail may now be raised from the sill 105 to the upper end of the frame 21 and locked in this position whereupon the tape lengths 34 and 35 of each tape assembly 31 and 32 secured to its bracket 40 by having its metal tip or clip 46 passed through the elongated apertures 44 and 45. The Venetian blind is now ready for normal operation.

If it were desired to replace the tape assemblies 31 and 32 along with the replacement of the raising and lowering cords 39 and 63 or if it were desired to retain the old raising and lowering cords but merely replace the tape assemblies the same procedure would be gone through with except that, in the case of merely replacing the tape assemblies 31 and 32, the cord knots 98 would not be disturbed.

If it were desired to replace the old style tape assemblies wherein the slat supports or ladder steps are alternately on opposite sides of its raising and lowering cord the procedure outlined in the above indicated co-pending application 667,870 would be followed, namely, a bracket 40 would be placed on the upper surface of the tilt bar near one end thereof with the arms projecting toward the cord of the tape assembly being replaced. This bracket would previously have had secured thereto one of the tape lengths 34 or 35 preferably that tape length on the opposite side of the Venetian blind from which the operator is working. The slat supports or ladder steps are placed each beneath its slat for the entire length of the Venetian blind whereupon

the remaining tape length is secured to the bracket 40. The ladder steps or slat supports of the old tape assembly is now cut from one of its tape lengths and removed from the Venetian blind. It is of course understood that the bottom rail remains in position due to its connection with the raising and lowering cords through the knot 97 or other connecting medium. The bracket 40 is now shifted to the position illustrated in Fig. 3 namely with its raising and lowering cord between its arms 42 and 43. At this point it should be noted that with a tilt bar having a notch or slot therein such as illustrated in Figs. 3 and 4 the opening thereof is closed by the arm 42 or 43 of the bracket which crosses it. With the bracket 40 in the desired position it is secured by screws 48. The lower ends 49 and 50 are now fastened to the under surface of the bottom rail 33 by tacks or the like.

The second tape assembly is now placed on the Venetian blind in the same manner as just described whereupon the Venetian blind is ready for a normal operation.

From the foregoing it will be appreciated that there has been provided a Venetian blind in which the raising and lowering cords can be replaced with a minimum of time and effort and without removing the blind or any part thereof from the opening with which it is being used. It will also be noted that the ladder tape assemblies 31 and 32 can likewise be replaced, on the job, by the average householder or utility person without the use of expert services. By the same token it should be noted that a considerable time saving is effected in the manufacture and assembly of Venetian blinds at the factory in that the heretofore time consuming operation of threading flexible raising and lowering cords through restricted apertures, cord lock housing, head rail channel slot, head rail outlet apertures and tilt bar apertures is eliminated to say nothing of threading the cord through the individual slat apertures.

In Figs. 15, 16 and 17 a slightly modified construction is illustrated which however will accomplish the same purpose. This construction consists of letting into the under side of the head rail 20 a groove or channel 106 through which the raising and lowering cords operate. The cord lock is identical with that above described except that it is placed nearer the under surface of the head rail 20 and at the same time the head rail 20 is provided from its inside face to the channel slot 106 with a notch or groove 107 thereby providing between its upper surface and the top of the locking mechanism front wall 69 an opening 108 whereby the cords may be inserted into the channel groove 106. Instead of utilizing pulley mechanisms 85 and 94 use is here made of removable pulleys 109 and 110 which are held in the channel groove 106 by removable pins 111 and 112.

The use of this modified mechanism is identical with that above described since the cord 39 would be placed around the pulley 110 after having been inserted through the individual slats and attached to the bottom rail 33 and the said

pulley 110 pushed into the channel groove 106 and the pin 112 then pushed home. The said raising and lowering cord 39 along with the raising and lowering cord 63 would then both be placed around the pulley 109 and it inserted into the channel groove 106 and its removable pin 109 pushed home to retain it in position. The said cords 39 and 63 would then be arranged within the locking mechanism 65.

- 10 If desired pulley mechanisms such as illustrated in Fig. 18 and indicated in general by the reference numeral 113 may be employed instead of the pulleys 109 and 110. This pulley mechanism 113 consists of a U-shaped bracket having a base 114 and depending arms 115 and 116 through which passes a removable pin 117 for securing the double grooved pulley 18 in position. The pulley mechanism 113 would be secured in position against the under side of an ungrooved head rail 20 by means of screws 119. The said pulley mechanisms 113 would be employed with a cord lock mechanism 65 mounted against the under surface of the head rail 20 in substantially the same manner as illustrated in Figs. 8 and 9.

From the foregoing it is believed now obvious that there has been provided a mechanism which will accomplish the objects initially set forth.

What is claimed is:

- 30 1. A cord guiding means for a Venetian blind comprising a head rail, a pulley mounting means secured to the under side of the head rail comprising a U-shaped bracket having one of its arms spaced from the head rail for permitting the placement of a raising or lowering cord into the bracket and over the pulley, and a second bracket adjacent one end of the head rail comprising a tubular casing with the pulley therein, and a slot in the casing through which slot a 35 cord may be positioned in locating the cord in the casing and about the pulley without threading the end of the cord through the casing.
- 40 2. A cord guiding means as in claim 1 wherein a locking device is rockably mounted in said casing.
- 45 3. A cord guiding means as in claim 1 wherein a locking device is rockably mounted in said casing comprising a jaw and a spring urging said jaw toward one side of the casing to clamp the 50 cord between the jaw and the casing.

CHARLES ADLER.
